Application June 23, 1949, Serial No. 100,896

13 Claims. (Cl. 246—161)

1
Our invention relates to control apparatus for electric locks for railway tracks switches. More specifically, our invention relates to means for releasing an electric lock for a railway track switch either promptly or upon the lapse of one or another measured period of time according to traffic conditions and according to the distance of the location of the switch in advance of a signal which governs traffic movements over the switch.

Operation of a railway track switch may be effected from a central or a distant point such, for example, as an interlocking tower or a dispatcher's office, or it may be effected locally. Operation of a railway track switch which is effected locally is usually accomplished by manual power applied through a manually operable switch operating lever direct to suitable mechanism for moving the switch between its normal and reverse positions.

Manually operable switch operating levers are equipped with padlocks in order to prevent movement of the switches by unauthorized persons. However, a railroad employee who has a switch padlock key might become confused or might misunderstand or forget an order or timetable regulation and might therefore open a switch padlock for moving the associated switch while it is unsafe to do so. If, for example, a trainman should erroneously reverse a switch for a train to move from an auxiliary track when a train is approaching at high speed on a main track in which the switch is located, there would probably be a collision between the two trains.

In order to protect against manual operation of a railway track switch while traffic conditions are such that it is unsafe for the switch to be operated, an electric lock, in addition to the switch padlock, may be employed. Heretofore, no provision has been made for having different lengths of release time for the electric locks for two or more switches in a block over which traffic movements are governed by the same signal. Also, no provision has been made, before applicants' invention, for releasing the electric lock for a switch upon the lapse of a given period of time after a train on a main track in which the switch is located passes the signal which governs traffic movements over the block in which the switch is located, and for releasing the electric lock for the same switch upon the lapse of a longer period of time when the switch is to be reversed for a train to move over the switch from an auxiliary track onto the main track.

An object of our invention is the provision of

2
means for releasing the electric lock for a switch promptly after a train passes a signal for the block in which the switch is located, if the switch is a short distance in advance of the signal, and for releasing a second switch in the same block which is a longer distance in advance of the signal upon the lapse of a longer period of time after the train passes the signal.

Another object of our invention is the provision of means for releasing the electric lock for a switch upon the lapse of a given measured period of time after the switch padlock for the switch is removed preparatory to reversing the switch for a train to move from an auxiliary track to a main track in which the switch is located, and for releasing the electric lock for the same switch either promptly after a train on the main track enters the block in which the switch is located or upon the lapse of a measured period of time which may be shorter than the given measured period of time according to the distance the switch is located in advance of a signal which governs traffic movements over the switch.

A feature of our invention for accomplishing these objects is the provision of a directional stick relay controlled in part by a track relay for a short track section which is located immediately in advance of a signal which governs traffic movements over a signal block in which one or more switches are located. In our invention, electric locks for switches which are located a short distance, less than 500 feet, for example, in advance of a signal are controlled directly by front contacts of the directional stick relay, and are therefore released promptly after a train, on a main track in which the switch is located, passes the signal. Also, in our invention, a time element device which has a relatively short operating time may be controlled by a front contact of the directional stick relay. Switches located between 500 and 3000 feet, for example, in advance of a signal are controlled by this time element device. A time element device which has a longer operating time is used for releasing each of the switches when a train movement is to be made from an associated auxiliary track to the main track, and is also used for releasing a switch when a train on the main track passes the signal for governing traffic movements over the switch, if the switch is more than 3000 feet, for example, in advance of the signal.

We shall describe three forms of apparatus embodying our invention, and shall then point out the novel features thereof in claims.

In the accompanying drawings, Fig. 1 is a

diagrammatic view showing one form of apparatus embodying our invention, in which a stretch of main railway track includes a signal block divided into a short section, designated by the reference character AT, adjacent and in advance of a signal, designated by the reference character IS, for governing traffic movements over the block, and a longer second section IT in advance of the short section; in which an approach section OT is shown in the rear of the signal; in which a directional stick relay ISR is arranged to become energized when a train passes the signal onto the short section, for effecting energization of an electric lock AWL for a first switch A in the second section a relatively short distance in advance of the signal; in which a time element device TER becomes energized for effecting energization of an electric lock CWL for a second switch C in the second section a longer distance in advance of the signal, upon the lapse of a given measured period of time after a train on the main track passes the signal; and in which the time element device TER becomes energized for effecting energization of one or both the electric switch locks AWL and CWL upon the lapse of the given measured period of time after the padlock for either switch is removed preparatory to reversing the associated switch for a train to move from an associated auxiliary track onto the second section.

Fig. 2 is a diagrammatic view showing a modified form of apparatus embodying our invention, in which two time element devices are employed, one of which, designated TER, has a relatively longer time of operation than the other which is designated ZTER; in which energization of the electric lock AWL for the first switch A in the second section is controlled by the directional stick relay ISR, as in Fig. 1; in which the first time element device TER, which has the longer time of operation, is controlled by a back contact of the directional stick relay ISR and by a contact which is closed when a traffic responsive decoding relay THR for the second section is deenergized while a track relay ATR for the first section is energized; in which the second time element device ZTER, which has the shorter time of operation, is controlled by a front contact of the directional stick relay ISR; in which the second switch C is controlled by the second time element device ZTER when a train on the main track passes the signal; and in which one or both switches may be controlled by the first time element device TER, as in Fig. 1, when either or both switches are to be reversed for a train to move from an associated auxiliary track onto the second section.

Fig. 3 is a diagrammatic view showing a modified form of the apparatus of Fig. 2, also embodying our invention, in which the first section 4RT in the block is within interlocking limits in an interlocking plant, and the second section A4T is outside of interlocking limits; and in which the signal R4S which governs traffic movements over the block is controlled by a lever 4V in an interlocking machine, and therefore normally displays the stop indication; in which the first time element device A4TER becomes energized when a track relay A4TR for the second section becomes deenergized, and the second time element device ZTER is controlled by a front contact of a stick relay 4ZSR, as in Fig. 2; and in which the switches are controlled by these time element devices, as in Fig. 2.

Similar reference characters refer to similar parts in each of the views.

Referring first to Fig. 1 of the drawings, a stretch of main railway track is shown, over which trains normally move in the direction indicated by the arrow, which we shall assume is the eastbound direction. The stretch of main track includes a signal block divided by insulated joints 2 into the short section AT adjacent, and in advance of, signal IS which governs traffic movements over the block, and the longer second section, designated by the reference character IT, in advance of section AT. The stretch of track also includes the approach section, designated by the reference character OT, in the rear of signal IS.

Each of the sections AT and OT is provided with a track circuit including a suitable source of current, such as a battery 3, connected across the rails adjacent one end of the section, and a track relay, designated by the reference character R preceded by the reference character for the associated section, connected across the rails adjacent the opposite end of the section. Section IT is also provided with a track circuit including a suitable source of current, such as a battery 3, connected across the rails adjacent one end of the section through a contact 5 of a coding device, designated by the reference character CT. Device CT is connected directly across terminals B and N of a suitable source of current, such as a battery Q, so that device CT is constantly energized, and therefore its contact 5 repeatedly closes and opens at a frequency which may, for example, be 180 times per minute. A code following track relay, designated by the reference character IT, is connected across the rails adjacent the opposite end of section IT.

Signal IS may be of any suitable design such, for example, as the well-known searchlight type. Signal IS governs eastbound traffic movements on the main track over section AT onto section IT.

A track switch A is shown in section IT a distance in advance of signal IS, which we shall assume is less than 500 feet, for example. A second track switch C is also shown in section IT a distance in advance of signal IS, which we shall assume is more than 3000 feet, for example.

Each of the switches A and C is provided with an electric switch lock, designated generally by the reference character WL, preceded by the reference character for the associated switch. Each of the electric switch locks AWL and CWL may be of any suitable design, such, for example, as the type of electric switch lock disclosed and claimed in a copending application, of common ownership, for Letters Patent of the United States, Serial No. 721,028 filed by Herbert L. Bone, George L. Temple, and John W. Logan, Jr. on January 9, 1947, for Electric Locks.

Each of the switch locks AWL and CWL includes an associated manually operable device, shown as a lever V, which has a normal position n, an intermediate position c and a reverse position r. Lever V is locked in its normal position n by a switch padlock. When the padlock is removed, lever V may be moved to its intermediate position c, in which a locking member 6 engages a dog 7. Further movement of lever V toward its r position is prevented until dog 7 has been lifted, by an electromagnet 8, out of engagement with locking member 6.

Switches A and C are operated by manual power applied through switch operating levers AV and CV, respectively, to switch mechanisms AW and CW, respectively. Levers AV and CV are locked in their normal position for retain-

ing switches A and C, respectively, in their normal positions, in which they are shown in the drawings, while switch lock levers V are in their *n* or *c* position. Levers AV and CV are released for operating switches A and C, respectively, only when lever V of switch lock AWL or CWL, respectively, is in its *r* position.

Lock contacts 9, 10, and 11, operated by lever V, are normally open, when lever V is in its *n* position, but become closed upon movement of lever V to its *c* position, and remain closed when lever V is moved on to its *r* position. Lock contact 9, upon becoming closed, completes a shunt path across the rails of section 1T, causing relay 1TR to be deenergized.

Energization of each of the lock magnets 8 is effected by an associated lock control relay, designated by the reference character WAR preceded by the reference character for the associated switch. Each of the lock control relays AWAR and CWAR is normally energized over a control circuit which includes conductors 65 and 66, through contact 24 of relay OTR, and through the front point of contact 23 of a relay 1HR, which is closed only while the track relays for sections AT and 1T are both energized. Relay CWAR is also controlled by contacts 25 and 27 of a time element device shown as a time element relay 1TER, either in response to a train entering the signal block for signal 1S, or in response to movement of lever V of switch lock CWL from its *n* position to its *c* position. Relay AWAR is also controlled by contacts 25 and 27 of relay 1TER in response to movement of lever V of switch lock AWL to its *c* position, and is controlled by contacts 38 and 39 of directional stick relay 1SR.

Traffic responsive decoding relays, designated by the reference characters 1FPR and 1HR are controlled by relay ATR and by code following track relay 1TR. An asymmetric unit, designated by the reference character *t* is connected across the winding of each of the relays 1FPR and 1HR in order to make these relays slow in releasing, so that they will retain their contacts in the picked-up position during the open periods of the front and back points, respectively, of contact 18 of relay 1TR, while relay 1TR is responding to coded current supplied to the opposite end of section 1T. Asymmetric units *t* may be of the well-known copper oxide half-wave rectifier type.

Time element device 1TER is controlled by contact 29 of relay 1FPR and the back point of contact 23 of relay 1HR.

Directional stick relay 1SR is controlled by relays ATR and 1HR so that it becomes energized when a train on the main track passes signal 1S onto section AT, and remains energized while the train occupies sections AT and 1T.

Signal 1S is controlled in part by a contact 22 of relay 1HR, and normally displays a proceed indication.

Referring next to Fig. 2 of the drawings, switch A is assumed to be less than 500 feet in advance of signal 1S, as in Fig. 1, but switch C is here assumed to be between 500 and 3000 feet in advance of signal 1S.

In Fig. 2, relay AWAR is controlled the same as in Fig. 1, but relay CWAR is controlled by the second time element device ZTER, in response to a train on the main track passing signal 1S onto the signal block. Relay CWAR is controlled otherwise as in Fig. 1.

Relay ZTER is controlled by a circuit which includes the front point of a contact 37 of relay 1SR, and relay 1TER is controlled by a circuit which includes a back point of contact 37 of relay 1SR. Relay 1TER closes its front contacts upon the lapse of a given measured period of time after it becomes energized. Relay ZTER closes its front contacts upon the lapse of a measured period of time which is shorter than the given measured period of time. It follows that, when a train on the main track passes signal 1S onto the signal block, relay CWAR may become energized upon the lapse of a shorter period of time than is required for relay CWAR to become energized when a train is to be moved from an auxiliary track over switch C onto section 1T.

Referring now to Fig. 3, the first section 4RT of the signal block is here within interlocking limits of an interlocking plant, and the second section A4T is outside of interlocking limits. Switch A is assumed to be less than 500 feet in advance of signal R4S, and switch C is assumed to be between 500 and 3000 feet in advance of signal R4S, similarly to switches A and C in advance of signal 1S in Fig. 2. A portion of another railway track X is shown, which intersects section 4RT.

Signal R4S may be of any suitable design such, for example, as the well-known searchlight type. Signal R4S governs eastbound traffic movements on the main track over a signal block which includes sections 4RT and A4T.

A signal of the searchlight type comprises various parts which we have grouped together for signal R4S, and designated as a signal mechanism R4m. Signal mechanism R4m comprises an optical unit, which has a single lamp E, and an operating element comprising a member 14 mounted to rotate in both directions as controlled by a signal winding 13. Attached to member 14 for rotation therewith between a normal position to the right and a reverse position to the left are three colored filters or roundels designated by the reference characters G, R, and Y which may be of the colors green, red, and yellow, respectively. Member 14 is biased to a mid stroke or intermediate position, to which it moves when the associated signal winding 13 is deenergized. When signal winding 13 is energized by current of the polarity which we shall term normal polarity, as shown in the drawing, member 14 is moved to the right-hand position.

For convenience in illustration, lamp E is shown above the roundels, but it is to be understood that lamp E is actually located directly behind one of the roundels according to the position of the member 14. Roundel G, R, or Y is moved in front of lamp E according as member 14 is moved to its right-hand position, its intermediate position, or its left-hand position, respectively. When lever 4V is moved to its *r* position, signal R4S is controlled to display a clear proceed indication, in which roundel G is placed in front of lamp E.

Operatively connected with member 14 is a circuit controller comprising two movable contact fingers 15 and 16. With signal R4S displaying the stop indication on account of its winding 13 being deenergized, as shown in the drawing, movable contact finger 15 engages a fixed contact element 15a, and movable contact finger 16 engages a fixed contact element 16a.

A signal of the type described is disclosed and claimed in Letters Patent of the United States

No. 1,864,224 granted June 21, 1932, to Wesley B. Wells for Light Signals.

A stop signal repeater relay, designated by the reference character 4PR, is controlled by the circuit controller for signal R4S, so that relay 4PR is normally energized while signal R4S is displaying the stop indication, but becomes deenergized when mechanism R4m is operated to a proceed position. Relay 4PR is made slow releasing by an asymmetric unit *t* connected across the winding of the relay.

An approach locking stick relay designated by the reference character 4ASR, associated with the signal R4S, is normally energized when relays 4PR and OTR are energized, and becomes deenergized when relay 4PR becomes deenergized when signal R4S is controlled to display a proceed indication. Relay 4ASR has a second pickup circuit which includes a back contact 43 of relay 4RTR and has a third pickup circuit which includes a contact 44 of a time element device shown as a relay 4TER. Relay 4TER is controlled by contact 41 of relay 4PR and by the back point of contact 45 of relay 4ASR.

Relays AWAR and CWAR are here controlled by relay 4ASR instead of by the relay OTR as in Fig. 2, but are controlled otherwise as shown in Fig. 2.

Having described, in general, the arrangement and control of the various parts of apparatus embodying our invention, we shall now describe the circuits and operation in detail.

As shown in the drawings, all parts of the apparatus are in the normal condition, that is, track sections OT, AT, and IT shown in Figs. 1 and 2, and sections OT, 4RT, and A4T shown in Fig. 3, are unoccupied, and therefore track relays OTR, ATR, 4TR, 4RTR, and A4TR are energized; signal 1S, shown in Figs. 1 and 2, is energized and displays a clear proceed indication, and signal R4S, shown in Fig. 3, is deenergized, and is therefore displaying a stop indication; each of the switches A and C is in its normal position; each of the electric lock levers V is locked in its *n* position by an associated switch padlock, and therefore contacts 9, 10, and 11 of each of the electric switch locks AWL and CWL are open; relays 1FPR and 1HR, shown in Figs. 1 and 2, relays AWAR and CWAR, shown in all figures, and relays A4FPR, A4HR, 4ASR, and 4PR, shown only in Fig. 3, are energized; and relays 1SR and 1TER, shown in Figs. 1 and 2, relay ZTER, shown in Figs. 2 and 3, relays 4ZSR, 4TER, and A4TER, shown in Fig. 3, are deenergized.

The circuit for relay 1FPR, shown in Figs. 1 and 2, passes from terminal B, through the front point of contact 17 of relay ATR, front point of contact 18 of relay 1TR, and the winding of relay 1FPR to terminal N. The circuit by which relay 1HR is energized, as shown in Fig. 1, passes from terminal B, through the front point of contact 17 of relay ATR, back point of contact 18 of relay 1TR, contact 20 of relay 1TER, contact 21 of relay 1FPR, and the winding of relay 1HR to terminal N. The circuit for relay 1HR, as shown in Fig. 2, is the same as the circuit shown in Fig. 1, except that it includes contact 19 of relay ZTER in addition to the contacts shown in Fig. 1. The circuit by which signal 1S is controlled to display a clear proceed indication includes contact 22 of relay 1HR.

The circuit by which relays AWAR and CWAR are energized, as shown in Figs. 1 and 2, passes

from terminal B, through the front point of contact 23 of relay 1HR, contact 24 of relay OTR, conductor 65, windings of relays AWAR and CWAR in multiple with each other, conductor 66, contact 26 of relay OTR, and the front point of contact 28 of relay 1FPR to terminal N.

We shall assume that, with apparatus embodying our invention as shown in Fig. 1, an eastbound train on the main track enters section OT. Contacts 24 and 26 of relay OTR therefore open the circuit just traced for relays AWAR and CWAR, causing these relays to become deenergized.

We shall assume further that a trainman from a train on an associated auxiliary track removes the padlock from lever V of switch lock AWL before the train on the main track arrives at signal 1S, so that contacts 9, 10, and 11 of switch lock AWL become closed. Contact 9 of switch lock AWL, upon becoming closed, completes a shunt across the rails of section IT, causing track relay 1TR to become deenergized. With relay 1TR deenergized, its contact 18 becomes opened at the front point, so that relay 1FPR is deenergized. With relay 1FPR deenergized, relay 1HR is in turn also deenergized because contact 21 of relay 1FPR is opened, causing signal 1S to display the stop indication because contact 22 of relay 1HR is opened.

With relays 1HR and 1FPR deenergized, time element relay 1TER becomes energized by a circuit passing from terminal B, through the back point of contact 23 of relay 1HR, winding of relay 1TER, and contact 29 of relay 1FPR to terminal N. Upon the lapse of a measured period of time after its energizing circuit becomes closed, relay 1TER closes its contacts 25 and 27, thereby completing a second circuit for energizing relays AWAR and CWAR, this circuit passing from terminal B, through the back point of contact 23 of relay 1HR, contact 25 of relay 1TER, conductor 65, windings of relays AWAR and CWAR in multiple with each other, conductor 66, contact 27 of relay 1TER, and the back point of contact 28 of relay 1FPR to terminal N. Relay AWAR, upon becoming energized by its pickup circuit through its upper control winding, as shown in Fig. 1 of the accompanying drawings, closes a retaining circuit including its lower winding, as shown in the drawing, this circuit passing from terminal B, through contact 40 of lock AWL, contact 32 of relay AWAR, contact 33 of relay AWAR, and contact 11 of lock AWL to terminal N.

With relay AWAR energized, the lock control winding 8 for lock AWL is energized by a circuit passing from terminal B, through contact 10 of lock AWL, contact 32 of relay AWAR, lock control winding 8, contact 33 of relay AWAR, and contact 11 of lock AWL to terminal N. Winding 8 of lock AWL, upon becoming energized, lifts its dog 7 out of engagement with the associated locking member 6, so that lever V of lock AWL can be moved to its *r* position, thereby releasing the operating lever AV for switch A.

If, instead of removing the padlock from lever V of lock AWL, a trainman of a train on an auxiliary track removes the padlock from lever V of lock CWL before a train on the main track arrives at signal 1S, signal 1S will be controlled to display the stop indication and control winding 8 of lock CWL will become energized similarly to the manner just described in connection with lock AWL.

If the padlock has not been removed from lever V of either switch lock AWL or CWL before the

train on the main track arrives at signal 1S, the train will pass signal 1S, and will deenergize relay ATR, causing relay 1HR to become deenergized, which in turn causes signal 1S to display the stop indication as previously described. Relay 1HR, on account of being slow releasing because of asymmetric unit *t* connected across its winding, retains its contact 36 closed at the front point for a brief period of time after contact 17 of relay ATR opens at its front point. During this brief period, directional stick relay 1SR will become energized by its pickup circuit passing from terminal B, through the back point of contact 17 of relay ATR, front point of contact 36 of relay 1HR, and the winding of relay 1SR to terminal N. Relay 1SR, upon becoming energized, completes its stick circuit passing from terminal B, through the back point of contact 17 of relay ATR, contact 37 of relay 1SR, and the winding of relay 1SR to terminal N. Contact 36 of relay 1HR, upon becoming closed at its back point, completes a second stick circuit for relay 1SR, this circuit passing from terminal B, through the back point of contact 36 of relay 1HR, contact 37 of relay 1SR, and the winding of relay 1SR to terminal N.

If, now, a trainman removes the padlock from lever V of switch lock AWL, relay AWAR will become energized by a second pickup circuit passing from terminal B, through contact 10 of lock AWL, contact 38 of relay 1SR, lower winding of relay AWAR, as shown in the drawings, contact 39 of relay 1SR, and contact 11 of lock AWL to terminal N. With relay AWAR energized, lock control winding 8 of switch lock AWL will first be energized in multiple with the lower winding of relay AWAR, through contacts 38 and 39 of relay 1SR, and will then be energized through contacts 32 and 33 of relay AWAR as before, and will lift its dog 7 out of engagement with locking member 6, so that lever V can be moved to its *r* position.

Lever V of lock AWL, upon being moved to its *r* position, unlocks the manual switch operating lever AV, so that switch A can be moved to its reverse position. If the train is moving faster than a slow speed such, for example, as 15 miles per hour, there will not be time for switch A to be operated before the train arrives at switch A, since switch A is assumed to be less than 500 feet in advance of signal 1S. Switch A can, however, be operated promptly after the train has passed it, because relay AWAR is energized by its circuit including contacts of relay 1SR.

As soon as relays 1HR and 1FPR become deenergized by the train passing signal 1S, relay 1TER will become energized by its circuit previously traced. Relay CWAR will then become energized upon the lapse of a measured period of time, as previously described.

For relay 1TER, a time element relay is selected which has an operating period of time longer than it will take a train traveling at a slow speed such, for example, as 15 miles per hour, to move from signal 1S to switch C. A train which is traveling faster than 15 miles per hour will therefore arrive at switch C before relay 1TER can close its contacts 25 and 27.

We shall next assume that, with apparatus embodying our invention modified as shown in Fig. 2, an eastbound train enters section OT, and that a trainman removes the padlock from lever V of switch lock AWL before the train arrives at signal 1S. Relay 1TR will therefore become deenergized, as previously described, because contact 9 of switch lock AWL will complete a shunt path across the rails of section 70 75 1T.

With relay 1TR deenergized, its contact 18 will become opened at the front point, so that relay 1FPR, and, in turn, relay 1HR, will become deenergized. Relay 1TER will then become energized by a circuit passing from terminal B, through the back point of contact 38 of relay 1HR, back point of contact 37 of relay 1SR, winding of relay 1TER, and contact 48 of relay 1FPR to terminal N. Contacts 25 and 27 of relay 1TER will become closed upon the lapse of a measured period of time for energizing relays AWAR and CWAR as previously described.

We shall now assume that all parts of the apparatus, modified as shown in Fig. 2, are again in the normal condition, and that an eastbound train passes signal 1S, causing relay 1SR to become energized as previously described in connection with Fig. 1. Relay ZTER will then become energized by a circuit passing from terminal B, through the back point of contact 36 of relay 1HR, front point of contact 37 of relay 1SR, the winding of relay ZTER, and contact 40 of relay 1FPR to terminal N. Upon the lapse of a measured period of time which is less than the period of time required for operation of relay 1TER, contacts 30 and 31 of relay ZTER become closed for energizing relay CWAR for releasing electric lock CWL sooner than if switch C were controlled only by relay 1TER, as shown in Fig. 30 1. The circuit by which relay CWAR is energized passes from terminal B, through the back point of contact 23 of relay 1HR, contact 30 of relay ZTER, conductor 65, winding of relay CWAR, conductor 66, contact 31 of relay ZTER, and the back point of contact 28 of relay 1FPR, to terminal N.

In the modified form of apparatus embodying our invention as shown in Fig. 3, relay 4ASR is normally energized, both a pickup and a stick circuit being closed. The pickup circuit which is closed passes from terminal B, through contact 41 of relay 4PR, contact 42 of relay OTR, and the winding of relay 4ASR to terminal N. The stick circuit passes from terminal B, through contact 41 of relay 4PR, front point of contact 45 of relay 4ASR, and the winding of relay 4ASR to terminal N. Relay A4FPR is energized by current passing from terminal B, through the front point of contact 46 of relay A4TR, and the winding of relay A4FPR to terminal N. Relay A4HR is energized by current passing from terminal B, through the back point of contact 46 of relay A4TR, contact 47 of relay A4FPR, and the winding of relay A4HR to terminal N. Relays AWAR and CWAR are normally energized by a circuit passing from terminal B, through the front point of contact 48 of relay A4HR, contact 49 of relay 4RTR, contact 50 of relay 4ASR, conductor 65, windings of relays AWAR and CWAR in multiple with each other, conductor 66, contact 53 of relay 4ASR, contact 56 of relay 4RTR, and the front point of contact 57 of relay A4FPR to terminal N.

We shall assume that, with the apparatus arranged as shown in Fig. 3, an eastbound train on the main track arrives on section OT, and that a leverman moves lever 4V to its *r* position for clearing signal R4S. With lever 4V in its *r* position, signal winding 13 will be energized by its circuit passing from terminal B, and including contact 12 of lever 4V, and winding 13 of signal R4S to terminal N. Member 14 of mechanism R4m will then be rotated toward the right for moving roundel G in front of lamp E. Contact 15—15a of signal R4S will therefore

be opened, causing relay 4PR to become deenergized. Relay 4ASR will therefore, in turn, also be deenergized, so that its contacts 59 and 53 will open the circuit traced for relays AWAR and CWAR, causing these relays to also be deenergized.

If the leverman then decides to return signal R4S to the stop position before the train on the main track passes signal R4S, he will return lever 4V to its *n* position, deenergizing winding 13. Member 14 of mechanism R4m will therefore return to its normal position in which it is shown in the drawing, so that the circuit controller again completes the circuit for energizing relay 4PR. Time element relay 4TER will therefore now be energized by a circuit passing from terminal B, through contact 41 of relay 4PR, back point of contact 45 of relay 4ASR, and the winding of relay 4TER to terminal N. Upon the lapse of a measured period of time, relay 4TER will close its contact 44, thereby completing a second pickup circuit for relay 4ASR, which is the same as the first pickup circuit traced for this relay except that it includes contact 44 of relay 4TER instead of contact 42 of relay OTR.

If, instead of returning signal R4S to the stop position before the train passes signal R4S, the leverman waits until after the train passes signal R4S, and then returns signal R4S to its stop position, relay 4ASR will become energized by a third pickup circuit passing from terminal B, through contact 41 of relay 4PR, contact 43 of relay 4RTR, and the winding of relay 4ASR to terminal N.

When the train enters section 4RT, deenergizing relay 4RTR, relay 4ZSR becomes energized by its pickup circuit passing from terminal B, through contact 58 of relay 4RTR, front point of contact 59 of relay 4AHR, and the winding of relay 4ZSR to terminal N, similarly to the manner in which relay 4SR becomes energized as described in connection with Fig. 1. If a trainman now removes the padlock from lever V of switch lock AWL, relay AWAR will become energized by a circuit which includes contacts 61 and 62 of relay 4ZSR, similarly to the manner in which relay AWAR becomes energized by a circuit including contacts of relay 4SR, as described in connection with Fig. 1. Relay ZTER will also become energized by an obvious circuit including contact 63 of relay 4ZSR. Upon the lapse of a measured period of time, relay CWAR will become energized by a circuit passing from terminal B, through the back point of contact 48 of relay 4AHR, contact 51 of relay ZTER, conductor 65, winding of relay CWAR, conductor 66, contact 55 of relay ZTER, and the back point of contact 57 of relay A4FPR to terminal N.

If, with the apparatus arranged as shown in Fig. 3, a trainman removes the padlock from lever V of switch lock AWL or switch lock CWL before a train on the main track passes signal R4S, relay A4TR will become deenergized, so that relay A4FPR will also become deenergized, and in turn relay A4HR will be deenergized. Relay 4TER will then be energized by a circuit passing from terminal B, through the back point of contact 49 of relay A4HR, winding of relay A4TER, and contact 64 of relay A4FPR to terminal N. Upon the lapse of a measured period of time, which is longer than the time required for operation of relay ZTER, relays AWAR and CWAR will become energized by a circuit passing from terminal B, through the back point of contact 48 of relay A4HR, contact 52 of relay

A4TER, line conductor 65, the winding of relay AWAR in multiple with the winding of relay CWAR, conductor 66, contact 54 of relay A4TER, and the back point of contact 57 of relay A4FPR to terminal N.

Although we have herein shown and described only a few forms of apparatus embodying our invention, it is understood that various changes and modifications may be made therein within the scope of the appended claims without departing from the spirit and scope of our invention.

Having thus described our invention, what we claim is:

1. In combination, a stretch of main railway track including a signal block, a signal for governing traffic movements over said main track onto said block, a track switch in said block a short distance in advance of said signal, a second track switch in said block a longer distance in advance of said signal, an electric lock for each of said switches each of which when deenergized locks the associated switch in its normal position, a directional stick relay energized in response to a train on said main track passing said signal onto said block, a stick circuit for then retaining said directional stick relay energized in response to said train on said block, means controlled by a front contact of said stick relay for energizing the electric lock for said first switch, a time element device, a contact of said time element device which becomes closed upon the lapse of a measured period of time after said time element device becomes energized, means for energizing said time element device in response to a train on said block, and means controlled by said contact of said time element device for energizing the electric lock for said second switch.

2. In combination, a stretch of railway track including a signal block, a signal for governing traffic movements over said track onto said block, a track switch in said block a short distance in advance of said signal, a second track switch in said block a longer distance in advance of said signal, an electric lock for each of said switches each of which when deenergized locks the associated switch in its normal position, directional means operated in response to a train on said track passing said signal onto said block, stick circuit means for then retaining said directional means in its operated condition in response to said train on said block, means responsive to operation of said directional means for energizing the electric lock for said first switch, and time element means operated in response to a train on said block for effecting energization of the electric lock for said second switch upon the lapse of a measured period of time after a train enters said block.

3. In combination, a stretch of railway track including a signal block, a signal for governing traffic movements over said track onto said block, a track switch in said block a short distance in advance of said signal, a second track switch in said block a longer distance in advance of said signal, an electric lock for each of said switches each of which when deenergized locks the associated switch in its normal position, directional means operated by pickup circuit means in response to a train on said track passing said signal onto said block, stick circuit means controlled by said train on said block for then retaining said directional means in its operated condition as long as said train occupies said block, means including said directional means in

its operated condition for effecting energization of the electric lock for said first switch, and means responsive to a train on said block for effecting energization of the electric lock for said second switch upon the lapse of a measured period of time after the train enters said block.

4. In combination, a stretch of railway track including a signal block divided into a first and a second section, a signal for governing traffic movements over said first section and then onto said second section, a stick relay controlled to become energized only if said second section is unoccupied when a train enters said first section and then to remain energized while said train occupies said second section, a track switch in said second section, an electric lock which when deenergized locks said switch in its normal position, and means controlled by a front contact of said relay for energizing said electric lock.

5. In combination, a stretch of railway track including a signal block which comprises a first portion between said signal and a switch and a second portion in which said switch is located, a signal for governing traffic movements onto said block, directional means operated in response to a train on said track passing said signal onto said first portion of said block only if said second portion is unoccupied, means responsive to occupancy of said second portion of said block by said train for then retaining said directional means in its operated condition, an electric lock which when deenergized locks said switch in its normal position, and means responsive to said directional means in its operated condition for energizing said electric lock.

6. In combination, a stretch of main railway track including a signal block which comprises a first portion between said signal and a switch and a second portion in which said switch is located, a signal for governing traffic movements onto said main track onto said block, directional means operated in response to a train on said main track passing said signal onto said first portion of said block only if said second portion is unoccupied, means responsive to occupancy of said second portion of said block by said train for then retaining said directional means in its operated condition, an electric lock which when deenergized locks said switch in its normal position, means responsive to said directional means in its operated condition for energizing said electric lock, and manually controllable time element means for effecting energization of said electric lock preparatory to operation of said switch for a train to enter said block from an auxiliary track.

7. In combination, a stretch of main railway track including a signal block, a signal for governing traffic movements onto said block, a track switch in said block, directional means operated in response to a train on said track passing said signal onto a first portion of said block between said signal and said switch, means responsive to occupancy by said train of a second portion of said block in which said switch is located for then retaining said directional means in its operated condition, an electric lock which when deenergized locks said switch in its normal position, means responsive to operation of said directional means for energizing said electric lock, a second track switch in said block farther from said signal than said first switch, a second electric lock which when deenergized locks said second switch in its normal position, time element means, and manually controllable means for energizing said time element means for effecting

energization of said first and second electric locks preparatory to operation of the corresponding switch for a train to enter said block from a first or a second auxiliary track respectively.

5. In combination, a stretch of railway track including a signal block, a signal for governing traffic movements onto said block, a track switch in said block, directional means operated in response to a train on said track passing said signal onto a first portion of said block between said signal and said switch, means responsive to occupancy by said train of a second portion of said block in which said switch is located for then retaining said directional means in its operated condition, an electric lock which when deenergized locks said switch in its normal position, means responsive to operation of said directional means for energizing said electric lock, a second track switch in said block farther from said signal than said first switch, a second electric lock which when deenergized locks said second switch in its normal position, time element means, and means controllable manually and in response to a train on said block for energizing said time element means for effecting energization of said first and second electric locks.

9. In combination, a stretch of railway track including a signal block, a signal for governing traffic movements over said track onto said block, a track switch in said block a short distance in advance of said signal, a second track switch in said block a longer distance in advance of said signal, an electric lock for each of said switches each of which when deenergized locks the associated switch in its normal position, means responsive to a train on said track passing said signal onto said block for effecting energization of the electric lock for said first switch, means responsive to a train on said block for effecting energization of the electric lock for said second switch upon the lapse of a measured period of time after the train enters said block, and traffic responsive means for energizing both of said electric locks if said block is unoccupied and if said track is also unoccupied a given distance in the rear of said signal.

10. In combination, a stretch of railway track including a signal block which comprises a first portion between said signal and a switch and a second portion in which said switch is located, a signal for governing traffic movements onto said block, directional means operated in response to a train on said track passing said signal onto said block only while said second portion of said block is unoccupied, means responsive to occupancy of said second portion of said block by said train for then retaining said directional means in its operated condition, an electric lock which when deenergized locks said switch in its normal position, means responsive to operation of said directional means for energizing said electric lock, manually controllable time element means for effecting energization of said electric lock preparatory to operation of said switch for a train to enter said block from an auxiliary track, and means responsive to traffic conditions on said track for effecting energization of said electric lock if said block is unoccupied and if said track is unoccupied a given distance in the rear of said signal.

11. In combination, a stretch of railway track including a signal block, a signal for governing traffic movements onto said block, a track switch in said block, directional means operated in response to a train on said track passing said signal

onto said block, an electric lock which when de-energized locks said switch in its normal position, means responsive to operation of said directional means for energizing said electric lock, a second track switch in said block farther from said signal than said first switch, a second electric lock which when deenergized locks said second switch in its normal position, time element means, means controllable manually for energizing said time element means for effecting energization of said first and second electric locks, means responsive to traffic conditions for also effecting energization of said time element means if said block is occupied by a train, and means responsive to traffic conditions on said track for effecting energization of both said electric locks if said block is clear and if said track is clear a given distance in the rear of said signal.

12. In combination, a stretch of railway track including a signal block divided into a first and a second section, a signal for governing traffic movements over said first section and then onto said second section, a stick relay controlled to become energized when a train enters said first section and then to remain energized while said train occupies said second section, a track switch in said second section, a second track switch in said second section farther from said signal than said first switch, an electric lock for each of said switches each of which when deenergized locks the associated switch in its normal position, a traffic responsive relay energized when said first and second sections are clear but deenergized when either of said sections is occupied by a train or is otherwise shunted, means controlled by a front contact of said stick relay for effecting energization of the electric lock for said first switch, a time element device, means controlled by back contacts of said stick relay and said traffic responsive relay for energizing said time element device, a second time element device, means controlled by a front contact of said stick relay for energizing said second time element device, manually controllable means associated with each of said electric locks for shunting the rails of said second section preliminary to unlocking the associated switch, means controlled by each of said time element devices for effecting energization of the electric lock for said second switch if said traffic responsive relay is deenergized, means controlled by said first time element device for effecting energization of the electric lock for said first switch, and means controlled

5 by traffic conditions for effecting energization of both said electric locks if said block is clear and if said track is clear a given distance in the rear of said signal.

13. In combination, a stretch of railway track including a signal block divided into a first and a second section, a signal for governing traffic movements over said first section and then onto said second section, a stick relay controlled to become energized when a train enters said first section and then to remain energized while said train occupies said second section, a track switch in said second section, a second track switch in said second section farther from said signal than said first switch, an electric lock for each of said switches each of which when deenergized locks the associated switch in its normal position, a traffic responsive relay energized when said second section is clear but deenergized when said second section is shunted, means controlled by a front contact of said stick relay for effecting energization of the electric lock for said first switch, a time element device, means controlled by a back contact of said traffic responsive relay for energizing said time element device, a second time element device, means controlled by a front contact of said stick relay for energizing said second time element device, manually controllable means associated with each of said electric locks for shunting the rails of said second section preliminary to unlocking the associated switch, means controlled by each of said time element devices for effecting energization of the electric lock for said second switch if said traffic responsive relay is deenergized, means controlled by said first time element device for effecting energization of the electric lock for said first switch, means for controlling said signal to display a proceed or a stop indication, and means controlled by traffic conditions for effecting energization of both said electric locks if said block is clear and if said signal is controlled to display the stop indication.
